Primary Examiner — Bridget L Eland(74) *Attorney, Agent, or Firm* — The Marbury Law Group, PLLC(57) **CLAIM**

The ornamental design for a network unit, as shown and described.

DESCRIPTION

FIG. 1 is a front right perspective view of the network unit, showing our new design;

FIG. 2 is a front view of the network unit of FIG. 1;

FIG. 3 is a rear view of the network unit of FIG. 1;

FIG. 4 is a left side view of the network unit of FIG. 1;

FIG. 5 is a right side view of the network unit of FIG. 1;

FIG. 6 is a top view of the network unit of FIG. 1; and,

FIG. 7 is a bottom view of the network unit of FIG. 1.

The broken lines shown in FIGS. 1-7 are for the purpose of illustrating portions of the network unit that form no part of the claimed design.
